CLAIM

We claim, the ornamental design for an injection molding machine, as shown and described.

DESCRIPTION

FIG. 1 is a perspective view of an injection molding machine, showing our new design;

FIG. 2 is another perspective view thereof;

FIG. 3 is another perspective view thereof;

FIG. 4 is a side view thereof, the opposite side being a mirror image thereof;

FIG. 5 is a front view thereof;

FIG. 6 is a top view thereof; and,

FIG. 7 is a rear thereof.

Portions shown in broken lines form no part of the claimed design.
